UNITED STATES PATENT OFFICE.

ANDREW F. CURTIN, OF MEDFORD, MASSACHUSETTS.

WATER-CLOSET INSTALLATION.

1,332,660.

Specification of Letters Patent.

Patented Mar. 2, 1920.

Application filed August 29, 1917. Serial No. 188,751.

To all whom it may concern:

Be it known that I, ANDREW F. CURTIN, a citizen of the United States, residing at Medford, in the county of Middlesex and 5 State of Massachusetts, have invented certain new and useful Improvements in Water-Closet Installations; and I do hereby declare the following to be a full, clear, and exact description of the invention, such as 10 will enable others skilled in the art to which it appertains to make and use the same.

The present invention relates to an improvement in water-closet installations. The object of the invention is to produce 15 a new form of installation of such construction that the tank is capable of being supported by the bowl, and serving to cover and conceal the connections between the tank and the bowl and the water connections to 20 the tank. To these ends the invention consists in the installation hereinafter described and particularly defined in the claims.

In the accompanying drawings illustrating the preferred form of the invention Figure 1 is a perspective view of the tank, Fig. 2 is a front elevation of the same, and Fig. 3 a sectional side elevation.

The tank illustrated in the drawing is 30 made of porcelain or other material, and consists of the tank proper 1 having the back wall 2, side walls 3, front wall 4 and the bottom 5 of the usual or any preferred form. The side and front walls of the tank 35 are continued downwardly below the bottom or floor of the tank to form an apron 6, which is extended downwardly sufficiently below the bottom of the tank to cover and conceal the inlet or supply pipe 7, the vent 40 pipe 8 and the flush pipe 9 extending from the bottom of the tank to the bowl. The middle or center portion 10 of the apron rests upon the bowl 11. This center portion of the apron is shown as longer than the remainder of the apron and as wide enough 45 to cover both the vent and the flush pipe whether the vent be made upon the one or the other side of the flush pipe. This center portion 10 of the apron forms a firm support for the tank.

It is to be observed that the appearance of the tank commends it by reason of its plainness and simplicity. To the observer it is not apparent whether the water inlet 55 be through the bottom of the tank or through the back wall of the tank. An im-

portant feature of the construction is that by virtue of which the tank is supported on the bowl by means of the center portion of the apron. The support of a tank is a matter that has received much attention from constructors, and a wide variety of more or less complicated and ingenious contrivances have been got up in the endeavor to produce a satisfactory tank support. All 60 such difficulty is eliminated by the tank of the present invention because its entire weight is supported upon the bowl. All that is necessary is to provide some simple means for holding it from lateral movement 65 and from tipping outward from the wall at the top. Such devices are simple in the extreme and the construction lends itself to use with ease to provide a firm, solid support 70 for the tank.

The apron forms a space of ample size to permit the making of proper connections for the flush pipe with the tank and with the bowl, and as the flush pipe is not visible 75 it can be of plain brass or other material 80 unnickled, and unprotected by porcelain cover, as the apron protects it from splashings from the closet. The position of the local vent in the wall varies with different installations, either by reason of the soil, or 85 ventilating pipes, or for other reasons, so it is not always possible to run the vent pipe straight back from the closet, nor to any other definite place, as to the right or to the left or at a certain distance from the 90 center on either side. This has heretofore required closet bowls to be made with right, left and center vents in order that the vent pipe might be properly connected with the 95 ventilating shaft. The present invention permits carrying the vent pipe from the bowl straight back or to the right or to the left as the position of the local vent in the wall requires. In the case in which the local 100 vent in the wall is central a single, plain elbow may be used. In case it is located at the right or at the left a pair of slip elbows is all that is necessary to make the proper connection, and wholly irrespective of the distance at which the vent in the wall is 105 located at either side. Whatever form of vent pipe is used, whether straight, right or left, it is fully protected by the apron and only one style of bowl is required for any 110 installation. Furthermore, the supply pipe may come from the wall anywhere within the space covered by the apron and lead to

the hole in the tank without being exposed to view. This pipe also may be of any material and it need not be provided with special finish, as it is entirely protected and concealed. The fact that the pipes are concealed renders the connections easy and convenient to make. It reduces the cost of the materials necessary to be employed for these connections, it facilitates installation because irregularity of appearance is immaterial, and the construction particularly commends itself to dealers in plumbing supplies because it reduces the number of forms of closets necessary to be carried in stock. This invention, therefore, commends itself to the manufacturer because of the reduced stock necessary to be carried; it commends itself to the plumber by reason of the facility of installation; it commends itself to the purchaser by reason of its reduced cost, and it commends itself to the user by reason of its plain, neat and sanitary appearance.

Viewed in its broader aspects, the invention contemplates providing a porcelain water closet tank with a connection concealing apron on its lower edge, whether such tank-supporting apron be of uniform depth throughout the perimeter of the tank or whether it extends to different depths at different portions thereof, and irrespective of whether it extends around the entire periphery of the tank or whether it extends only around a part thereof, as illustrated in

the drawings, wherein the depending connection concealing apron is of uniform depth except at center, where it is longer, or deeper in order to reduce the apparent vertical height of the tank. 35

The word "porcelain" in the claim is intended as a word of description and not of limitation, for it is apparent that, as above suggested, the tank may be made of other material. 40

Having thus described the invention what 45 is claimed is:

1. A water closet installation comprising a bowl having a rearwardly extended portion of less width than the body portion of the bowl, a porcelain tank and connections 50 between the tank and bowl, the tank having an apron depending from the lower end thereof, one portion of which is extended downwardly beyond the other portions and rests upon said rearward extension of the 55 bowl so that the weight of the tank is supported solely by the bowl.

2. A water closet installation comprising a bowl having a rearwardly extended portion, the tank having the body portion 60 thereof spaced some distance above the bowl and connections without the tank between the bottom thereof and the bowl, the tank having a depending apron resting upon said rearwardly extending portion arranged so 65 that the weight of the tank is supported solely by the bowl.

ANDREW F. CURTIN.
